METHOD OF FABRICATING WELL HEADS

David C. Walker, Tulsa, Okla., assignor to Walker Well Heads Inc., Tulsa, Okla., a corporation of Oklahoma

Application November 16, 1951, Serial No. 256,781

2 Claims. (Cl. 29—480)

This invention relates to improvements in well heads for oil and gas wells and the like, and more particularly, but not by way of limitation, to an improved well head body and a method of fabricating the same.

As it is well known, the well head bodies utilized on oil and gas wells comprise a large coupling of a size to connect directly with the well casing and two smaller couplings secured to diametrically opposite sides of the larger coupling. These well head bodies are usually either forged or cast as an integral unit. It will be apparent that the casting or forging of an article of such configuration is a delicate and time consuming operation. Furthermore, both the large and small couplings must be provided with internal threads after the casting or forging operation, which entails various threading machine set-ups and changes, as well as a considerable length of machine time. The cost of these well head bodies is, therefore, unnecessarily increased. Heretofore it has been impractical to fabricate the well head bodies from standard size couplings because of the distortion of the threads during and subsequent to the welding of the smaller couplings onto the large coupling.

The present invention contemplates a novel well head body fabricated from standard size couplings. Apertures are formed in the walls of a large coupling and then the outer surface of the larger coupling is machined around each aperture in such a manner to receive smaller couplings prior to the welding of the couplings. Also, a tapered plug is wedged into the large coupling prior to the welding operation. In this manner, the internal threads of the large coupling are precluded from distorting upon cooling of the metal subsequent to the welding operations. Thus, the small couplings may be efficiently welded to the large coupling and the threads of the large coupling will retain their original size and configuration. The resulting well head body may be manufactured and distributed at a very material saving as compared to a forged or cast well head body.

An important object of this invention is to provide a well head body which may be economically manufactured.

Another object of this invention is to provide a novel method of fabricating a well head body from standard sized couplings.

A further object of this invention is to provide a novel method of fabricating a well head body from standard sized couplings wherein the internal threads of the couplings will not be distorted during the fabricating operations.

A still further object of this invention is to provide a well head body having standard threads for simple and convenient connection with various conduits at the surface of a well, and having a long service life.

Other objects and advantages of the invention will be evident from the following detailed description, read in conjunction with the accompanying drawings, which illustrate my invention.

2

In the drawings:

Figure 1 is an elevational view of a novel well head having a quarter section removed to expose the internal structure thereof.

Figure 2 is an elevational view of the well head body illustrating the machined surfaces of the large well head body coupling.

Figure 3 is a partial sectional view taken along lines 3—3 of Fig. 2 with a portion of the well head body shown in plan.

Referring to the drawings in detail, and particularly Fig. 1, reference character 2 generally indicates a well head having a novel body portion generally indicated at 4. The well head body 4 comprises a large standard sized coupling 6 of a size to connect directly with the well casing (not shown). Two smaller standard sized couplings 8 are connected to diametrically opposite sides of the larger coupling 6 to form the completed well head body.

In fabricating the body 4, radially extending apertures 10 are first formed in diametrically opposite sides of the larger coupling 6 substantially in the central portion of the coupling. The outer surface of the coupling 6 around each of the apertures 10 is then machined or cut away as illustrated in Figs. 2 and 3. The areas 12 and 14 directly above and below each aperture 10 are cut away in such a manner to completely receive the upper and lower portions of the respective coupling 8. In machining the areas 12 and 14 to flat surfaces, shoulders 13 and 15 are formed which overlie the outer surface of the respective coupling 8 when the body 4 is assembled as shown in Fig. 1. Additional machine surfaces or fly cuts 16 are provided on each side of each aperture 10 to interconnect the areas 12 and 14. The areas 16 are machined to a flat surface to receive a portion of the inner end 18 of the respective coupling 8. It will be apparent that the width of the machined areas or surfaces 16 is limited by the wall thickness of the larger coupling 6, since the areas 12, 14 and 16 should be in the same vertical plane. In actual practice, the width of each area 16 is approximately one-third as large as the width of the areas 12 and 14.

After the machining operation, the ends 18 of the couplings 8 are placed in abutting relationship with the respective areas 12, 14 and 16 and are then welded, as illustrated in Fig. 1. The couplings 8 are preferably formed from one standard sized coupling by merely cutting the standard sized coupling in half. The inner ends 18 of each coupling 8 should be flat in order to make good contact with the machined areas 12, 14 and 16, and are preferably machined in order to make a proper contact. Prior to the welding operations, a rigid tapered plug (not shown), preferably formed out of steel, is wedged into the upper end 20 of the large coupling 6. The tapered plug is preferably formed on the same taper as the threads 22 in the upper portion of the large coupling 6 in order to contact the crest of each thread and prevent contraction of the threads. The threads 22 are machined with a taper amounting to approximately three-quarter inch to one foot. This is normal in compliance with API specifications. Furthermore, the threads 22 may be slightly rounded if desired at the ends thereof in order to facilitate the removal of the conforming tapered plug. The tapered threads 24 in the lower portion of the coupling 6, which connect with the well casing, are not appreciably affected by the welding operation, therefore, no plug is required in the lower portion of the coupling.

During the welding operation, the metal of both the couplings 8 and the coupling 6 will obviously expand by the inherent application of the heat. After the welding operation, the metal of both the couplings 8 and the couplings 6 will obviously contract. However, the metal

of the coupling 6, in proximity with the apertures 10, contracts to a greater degree than the diameters of the couplings 8. Thus, the shoulders 13 and 15 in effect shrink upon the end 18 of the respective coupling 8 to assist the welding metal in providing a rigid connection. It will be apparent that the tapered plug (not shown) prevents undue contraction, and therefore distortion, of the threads 22 in the coupling 6, and particularly adjacent the apertures 10. The couplings 8 do not expand or contract to such an extent to damage the threads 26 therein.

To form the completed well head 2, a slips or hanger bushing 28 is threaded into the upper end 20 of the large coupling 6. A circumferential groove 30 is preferably provided in the outer surface of the bushing 28 to receive an O-ring 32 and prevent leakage of fluid around the bushing 28. The O-ring 32 engages the upper inner surface of the coupling 6 above the threads 22. An outwardly extending circumferential flange 34 is provided on the upper end of the bushing 28 and has a plurality of notches 36 therein to receive a suitable turning tool (not shown) and facilitate the assembly of the bushing 28 in the well head body 4.

The lower inner surface 38 of the bushing 28 is tapered downwardly and inwardly to receive a plurality of slip members 40. Any number of slips 40 may be provided and they are preferably interconnected by a suitable locking ring 42. Serrations or teeth 44 are provided on the inner surface of each slip member 40 to engage the outer surface of the well tubing 46. It will be apparent that upon downward movement of the slips 40, the tapered surfaces 38 force the slips 40 inwardly into contact with the tubing 46.

A pack-off or sealing ring 48 is disposed above the slip members 40 to provide a seal between the bushing 28 and the well tubing 46. Suitable metallic rings 50, usually called "junk" rings, are provided above and below the pack-off 48 to facilitate compression of the pack-off 48 in the usual manner. An apertured packing nut 52 is threadedly secured in the upper end of the bushing 28 to provide a downward force on the junk rings 50 and pack-off 48. Transverse aperture 54 may be provided in the upper end of the packing nut 52 to facilitate rotation of the nut 52, if desired.

From the foregoing, it is apparent that the present invention provides a simple and rugged well head body which may be economically manufactured. The present invention also provides a novel method of fabricating a well head body from standard sized couplings in such a manner that the threads of the body will not be distorted,

and the side couplings will be rigidly connected to the larger coupling.

Changes may be made in the combination and arrangement of parts as heretofore set forth in the specifications and shown in the drawings, it being understood that any modification in the precise embodiment of the invention may be made within the scope of the following claims without departing from the spirit of the invention.

I claim:

1. A method of fabricating a well head body from a large and two smaller internally threaded couplings, comprising the steps of forming two diametrically opposed radially extending apertures in the wall of the large coupling, fly cutting the apertures to provide flat machined areas on the outer surface thereof, wedging a tapered plug in the large coupling against the crests of the threads therein, welding one end of each of the smaller couplings to each of said flat machined areas of the outer surface of the large coupling immediately adjacent the apertures, and retaining the plug in the large coupling subsequent to the welding operation to preclude any substantial distortion of the threads in the large coupling.

2. A method of fabricating a well head body from a large and small internally threaded couplings, comprising the steps of forming a radially extending aperture in one wall of the large coupling, machining the outer surface of the large coupling around the aperture to provide a flat surface of a size corresponding to the cross sectional size of the smaller coupling with outwardly extending shoulders above and below the flat surface, wedging a tapered plug in the large coupling against the crests of the threads therein, placing one end of the smaller coupling in contact with the flat surface and the adjacent faces of the outwardly extending shoulders, welding the smaller coupling to the larger coupling to the said machined surface, and retaining the plug in the large coupling subsequent to the welding operation to preclude distortion of the threads in the large coupling.
